US0D1109053S

(12) **United States Design Patent** (10) **Patent No.:** **US D1,109,053 S**
(45) **Date of Patent:** **** Jan. 13, 2026**

(54) **CATAMARAN**

(71) Applicant: **Xtramarine**, Nice (FR)

(72) Inventor: **Giuseppe Conti**, Nice (FR)

(**) Term: **15 Years**

(21) Appl. No.: **35/521,696**

(22) Filed: **Mar. 15, 2024**

(80) **Hague Agreement Data**

Int. Filing Date: **Mar. 15, 2024**

Int. Reg. No.: **DM/238392**

Int. Reg. Date: **Mar. 15, 2024**

Int. Reg. Pub. Date: **Jul. 19, 2024**

(51) **LOC (15) Cl.** **12-06**

(52) **U.S. Cl.**

USPC **D12/304**

(58) **Field of Classification Search**

USPC D12/3, 174, 300, 301, 304, 311, 317
CPC . B63B 7/08; B60F 3/00; B60F 3/0061; B63H

2021/216
